UNITED STATES PATENT OFFICE.

ZENAS U. DODGE, OF NEW YORK, N. Y., ASSIGNOR TO UNITED ICE IMPROVEMENT COMPANY, OF NEW YORK, N. Y., A CORPORATION OF DELAWARE.

APPARATUS FOR MAKING ICE.

1,074,417.

Specification of Letters Patent. Patented Sept. 30, 1913.

Application filed November 21, 1912. Serial No. 732,758.

To all whom it may concern:

Be it known that I, ZENAS U. DODGE, a citizen of the United States, residing at New York, in the county and State of New York, 5 have invented certain new and useful Improvements in Apparatus for Making Ice, of which the following is a specification.

This invention relates to apparatus for making ice and more particularly to certain 10 improvements in the construction of the ice cans and brine conduits employed in systems of the type disclosed in my prior application Serial No. 717,266, filed August 27, 1912.

The objects of the invention are to provide 15 a simple construction whereby the pipes forming the interior brine circulating conduits of the cans are carried by the can so that the cans may be readily and conveniently placed in position in the freezing tank.

20 The novel features of the invention will be apparent from the following description taken in connection with the accompanying drawings, in which:

Figure 1 is a fragmentary longitudinal 25 section of a freezing tank with one of the ice cans shown in section. Fig. 2 is a transverse section of the tank shown in Fig. 1, on a reduced scale. Fig. 3 is a fragmentary longitudinal section of one of the ice cans 30 and a portion of the bottom of the freezing tank. Fig. 4 is a transverse section on the line 4—4 of Fig. 3. Fig. 5 is a transverse section of a detail.

Referring to the drawings, 10 indicates a 35 freezing tank which may be of any suitable construction and has arranged on the bottom thereof a series of conduits 11, on which rest the ice cans 12. The conduits 11 are supplied with brine from a suitable header 40 13. At the top of the tank 10 are arranged the intersecting beams 14 which form spaces for the purpose of receiving the ice cans 12 and guiding the latter to their proper position on the conduits 11. The spaces above 45 the ice cans may be closed by means of suitable covers 15 which are supported by the beams 14.

The ice cans are constructed with sheet 50 metal sides and with a heavy cast plate 16 in the bottom, this plate having recesses or pockets 17 in its lower side and openings into which are secured in any suitable manner, as by means of the ordinary screw threads, the upwardly extending brine circulating tubes 18. These tubes preferably

have their upper ends closed and a tight joint is made at their lower end by means of nuts 19 and suitable gaskets 20.

A dome-shaped shoe 21 having an extension 22 on its upper side is secured within each of the tubes 18 by being screwed or driven into the same, and has extending vertically therethrough an opening, in which is secured the tube 23. The tubes 23 are concentrically arranged within the tubes 18 and have their upper ends open, the lower ends of these tubes being in communication with the under side of the shoe 21.

The conduit 11 is provided with outlets 24 in its top, these outlets registering with the brine circulating tubes 18. The brine circulates from the conduits 11 upwardly through the outlets 24 and the tubes 23 and downwardly through the annular space between the tubes 18 and 23 to the space below the bottom plate 16, suitable grooves 26 being provided in the extension 22 of the shoe 21 for the purpose of permitting the brine to escape. From Fig. 2 it will be observed that the sides of the can extend beyond the sides of the conduits 11 so that ample space is provided for the escape of the brine from under the plate 16.

For the purpose of providing a tight joint between the lower face of the shoes 21 and the top of the conduits 11 any suitable packing means may be provided and for this purpose I have shown in Fig. 3 annular gaskets 27 surrounding the outlets 24, these gaskets being preferably secured to the top of the conduit. Instead of this construction that shown in Fig. 5 may be used, in which the shoe 21 has an annular groove in its lower face, and a suitable gasket 28 is secured in this groove.

From the foregoing description it will be obvious that since the cans are guided by the beams 14 when being placed in position the brine circulating tubes of the cans will always register with the conduit outlets 24, and since the tubes 18 and 23 are both carried by the can there is practically no liability of damaging the tubes in handling the cans. Since the weight of each can is carried by the shoes 21 a tight joint will always be formed between the shoe and the top of the conduit and prevent any material amount of leakage from the space under the shoe directly to the space below the bottom of the can.

110

It will be obvious that various changes may be made in the minor details of construction, within the scope of the appended claims, and therefore I do not wish to be limited to the exact details shown and described.

Having thus described the invention what is claimed as new is:

10. 1. In an apparatus for making ice, the combination of a freezing tank, a brine conduit, at the bottom of the tank, having an outlet in its top, an ice can supported on said conduit and provided with a brine circulating tube extending upwardly from its bottom and communicating through the bottom with the interior of the tank, a second tube secured to said can and arranged within the first tube, and means connecting said second tube and said conduit outlet.
20. 2. In an apparatus for making ice, the combination of a freezing tank, a brine conduit, at the bottom of the tank, having a plurality of outlets in its top, an ice can arranged in the tank above said conduit and having a plurality of brine circulating tubes extending upwardly from the bottom and communicating through the bottom with the interior of the tank, tubes secured to the can and arranged within said circulating tubes, and means supporting the can on said conduit and establishing communication between said conduit outlets and said second-mentioned tubes.
30. 3. In apparatus for making ice, the combination of a freezing tank, a brine conduit, at the bottom of the tank, having an outlet in its top, an ice can arranged in the tank above said conduit and having a brine circulating tube secured in an opening through the bottom of the can and extending upwardly therefrom, a member secured to the bottom of the can and covering the outlet

in said conduit, said member having an interior opening in communication with said outlet, a tube arranged within said circulating tube and secured in said member and adapted to convey brine from said conduit outlet to the upper part of said circulating tube, and means for conveying brine from the lower part of said circulating tube to the exterior of said can.

4. In apparatus for making ice, an ice can having sheet metal sides and a cast metal bottom plate, said bottom plate having an opening therethrough, a brine circulating tube closed at its upper end and having its lower end secured in said opening, a hollow plug secured in the lower end of said tube and provided with an opening or groove adapted to convey brine from the tube to the space below said bottom plate, and a tube secured in said plug and arranged within said first-mentioned tube.

5. In apparatus for making ice, a tank having a brine conduit at the bottom thereof, said conduit being provided with an outlet in its top, an ice can arranged in said tank above said conduit and having an opening through the bottom thereof in registration with said conduit outlet, a brine circulating tube secured in said opening and extending upwardly therefrom, a member secured to the bottom of said can surrounding said conduit outlet, packing means between said member and said conduit, and a tube arranged within said first-mentioned tube and secured to said member.

In testimony whereof I affix my signature in presence of two witnesses.

ZENAS U. DODGE.
